UNITED STATES PATENT OFFICE.

BENJAMIN F. JOLINE, OF TOTTENVILLE, NEW YORK, ASSIGNOR TO THE JOLINE CORPORATION, OF NEW YORK, N. Y., A CORPORATION OF NEW YORK.

PRINTING-MACHINE.

1,202,393.

Specification of Letters Patent. Patented Oct. 24, 1916.

Application filed December 21, 1915. Serial No. 37,966.

To all whom it may concern:

Be it known that I, BENJAMIN F. JOLINE, a citizen of the United States, residing at Tottenville, in the county of Richmond and State of New York, have invented certain new and useful Improvements in Printing-Machines; and I do declare the following to be a full, true, and exact description of the said invention, such as will enable others skilled in the art to which it appertains to make and use the same.

This invention relates to a printing machine in which a relatively small number of printing forms, words, letters or figures, or any of them, are mounted on movable supports in order to bring them into selected groups desired for the purpose of printing any desired line of words or figures. Such a construction is particularly adapted for use in writing the amounts to be paid on checks or the like.

One of the objects of the invention is to provide a simple and efficient mechanism in which the different words may be readily grouped by the operator as desired.

With this and other objects in view, my invention consists of certain novel features of construction, combination and arrangement of parts as will be more fully described and pointed out in the appended claims.

In the drawings, Figure 1 is a front elevation of one form of my novel mechanism which I have selected for purposes of illustration, such machine being in this instance, a device particularly adapted for printing the exact amount in words and figures for which a check is drawn. Fig. 2 is a plan view of Fig. 1; Fig. 3 is a sectional elevation of Fig. 1 taken on an irregular line running along or in front of the line 3—3 of Fig. 5; Fig. 4 is a bottom view of Fig. 3; Fig. 5 is a sectional elevation on the line 5—5 of Fig. 1; Fig. 6 is an enlarged view of the detent shown in Fig. 5; Fig. 7 is an enlarged view of the segment supports on the line 7—7, Fig. 5; Figs. 8 and 9 are enlarged views showing respectively the end and the side view of the printing wheel in the act of printing; and Fig. 10 shows an alternative form for the arrangement shown in Fig. 9.

The corresponding parts are referred to both in the drawings and in the specification by similar reference characters.

In the drawings, 10 represents a base or platform having the upstanding arm 11 sup-

porting a split bearing 12 which carries one end of a fixed shaft 13. A screw 14 serves to clamp the split bearing. A web 15 extends from the support 10 to the bearing 12 to support various parts of the mechanism as will be pointed out hereafter.

On the shaft 13 is rotatably mounted a member 16 having a hub 17. A plate 18 held by the screws 19, by engagement in a groove in the end of the shaft 13, serves to hold the member 16 against longitudinal motion. The member 16 carries preferably a plurality of printing segments numbered 21—26 respectively, although it will be understood that for some purposes only one of these segments will be needed. Each of these segments is supported on the hub 17 of the member 16 so that it may be moved longitudinally of the axis of member 13. Many forms of construction may be adopted to enable this to be done, but preferably I provide each of the segments 21—26 with an axle 27 which lies in a half-round slot milled across the circumference of the hub 17 as shown best in Figs. 5 and 7. This hub is also slotted longitudinally to permit the lower ends of the segments to swing therein. As a convenient means for preventing the axles 27 from falling out of the slots in the hub 17, I provide a sleeve 28 which fits over the hub 17 and over the tops of the axles 27 to hold the latter in place. From the foregoing description, it will be seen that each of the segments is mounted on a shaft or axle held rigidly to the hub 17. At 27' of Fig. 7 I have shown a slightly modified form of this support, in which, if necessary, two printing segments may be supported on a single shaft or axle. This special arrangement is necessary where spacing must be prevented between succeeding words, each of which is mounted on an independently movable segment. In the form illustrated this occurs between the tens and the units of the amount to be written in cents.

The printing segments 21—26 are curved as shown best in Fig. 5, and preferably on a radius struck from the center of the axles 27. On the outer surfaces of the segments 21—26 are provided lines of printing forms as shown in Fig. 2, preferably in raised letters of the ordinary type character. Each of the printing segments is provided with a pawl or detent 29, yieldingly held in contact with notches in the sides of the segments so that the segments are temporarily locked in

any given position to which they may be moved. For purposes of moving them, each of the segments is provided with a projection carrying a combined handle and index pointer 30 which projects through a slot in the cover 31, the cover carrying adjacent each of the slots appropriate markings to indicate the matter on the printing surface of the printing segments which has been brought into printing relation when the handle index has been moved to one of the markings on the cover 31. Preferably to prevent any shake or looseness on the axle 27 in the direction of its length, I provide side bearings for the printing segments such as the curved arms 32 projecting from and connected to the member 16. These surfaces are finished so that the arm segments slide between them with a sufficiently tight fit to prevent the segments from rocking sidewise on their axles.

The segments 21-26 and the rotatable member 16 together constitute a printing wheel which prints by rotating the member 16. Such rotation may be obtained by any suitable means such as a handle 33 connected to the cover 31 and through that to the member 16. The printing is effected by rotating the printing surfaces on this printing wheel in contact with an impression member such as the wheel 34 to be more fully described hereafter. This impression member is preferably located in a plane passing through the axles 27 at right angles to the shaft 13, and any desired combination of the words on the segments 21-26 may be obtained by moving each of the segments until the appropriate word thereon is in such plane. Then on rotation of the member 16 by the handle 33 these words, brought into printing relation, will be printed on a sheet passing between the printing wheel and the impression member. Obviously it is desirable that when such printing is taking place, each of the printing surfaces on the respective segments shall form part of a circle having the center of the shaft 13 as its center. For that reason the printing surfaces on the segments 21-26 are curved in the direction longitudinal of their axles 27 on a radius equal to the sum of the radius of the printing surface from the axle 27 and the distance between the center of the axle 27 and the center of the shaft 13. Such a curve will, of course, respond to the condition provided above: that is to say, when such a surface is swung into the line 3-3 of Fig. 5, it will form part of a circle having the center of the shaft 13 as its center. With the segments thus curved, it is obvious that by moving the handle index 30 in an appropriate manner, any given line to be printed may be brought into the plane passing through 3-3 of Fig. 5, and when the member 16 is rotated by the handle 33 these printing surfaces on the segments will

have the relation indicated in the partial section of Fig. 9.

While the impression member may be of any suitable form, I preferably make it in the form of a roller or wheel as shown particularly at 34 of Fig. 9. Preferably I mount this roller or wheel on a yoke 35 pivoted at 36 on the support 10, and beneath the upper surface or platform thereof. This yoke 35 is held upward by spring 37 on a screw 38, but the upward motion of the roller 34 is limited by the adjusting screw 39. It will be seen from this construction that the wheel 34 is rotatably mounted and is held in contact with the printing surfaces 30 yielding but in such a way that when the surfaces are out of contact, spring 37 may not move it unduly upward. I have also provided a paper guide 40 which is adapted to engage the edge of the sheet passing between the printing wheel and the impression member. This paper guide is adjustably connected to the support 10 and is controlled by a rack 41 which is engaged by a pinion 42 and shaft 43 connected to the knurled handle 44. I also preferably provide a paper clamp for holding the sheet to be printed. The special function of this paper clamp will be pointed out hereinafter. As preferably constructed, it consists of a relatively rigid clamp 45 pivotally connected at 46 to the support 10 and normally pressed downward in contact with the support 10 or some portion thereof by a coil spring 47. Preferably I make this clamp 45 segmental in cross section and cause it to engage with a segmental projection 45' on the base 10. This paper clamp is provided so as to hold the paper just in advance of the printing point of the machine. I provide a handle 48 pivoted at 49 as a convenient means for opening the paper clamp to insert a new sheet. This handle 48 engages with a projection on the clamp 45 extending to the rear of the pivot 46 and through the web 15. For some purposes I also provide a projection 50 on the cover 51 which acts as a cam to strike a projection 52 on the clamp 45 when the printing wheel is brought to the position shown in Fig. 1 and thus open the paper clamp. In order to prevent smearing of the sheet being printed by any of the printing surfaces other than those selected, I provide a guard 53 of a very light sheet metal, preferably brass, which is connected at one end to the clamp 45, and which is provided with a slot 54 through which the impression wheel 34 may extend. This guard 53 prevents any of the printing surfaces on the segments, except the one in line with the impression member 34, from touching the sheet being printed.

As a means for inking the type surfaces, I provide the felt wheel 55 which may be charged with suitable ink and which is ro-

tatably mounted on a screw 56 in the member 57. This latter member is provided with a socket into which projects a shaft 58 which is held therein by a thumb screw 59. 5 The shaft 58 passes through an elongated hole in the web 15 and is held pivotally therein by the screw 60. Through a spring 61 acting against a plate 62 connected to the shaft 58, the inking wheel 55 is held 10 yieldingly against the printing surfaces as the latter pass it during the printing operation. Through the connection 59 the printing wheel 56 and the member 57 may be readily removed from the machine so as to 15 charge the printing wheel with a fresh supply of ink.

15 It is preferable that the printing wheel
be held in a fixed non-printing position
after the printing operation is completed.
20 but before the next operation is begun. This
brings the indices always in a definite rela-
tion to the operator, and at the same time,
frees the platform 10 so that the printed
sheet may be removed and a new one in-
25 serted ready for the next operation. To
this end I provide the detent device, which,
for the purposes of illustration, is shown
as a round headed pin 63 working in a
socket 64 connected to the web 15 and
30 thrown forward by a spring 65. The rear
of the cover 51 is provided with a hole with
which the pin 63 engages when the wheel is
in the desired non-printing position. To
facilitate the entry of the pin 63 as the
35 wheel is completing its printing stroke, I
provide the incline surface 66 in the cover
51 which leads to the hole in the cover 51
engaged by the pin 63. As ready means for
operating this detent, I provide the rod 67
40 supported in suitable bearings in the mem-
ber 16 and the cover 31, and provided with
the head 68 adjacent to the handle 33. The
operator with the knuckle of one of the
45 fingers of the hand engaging the handle 33
may readily push the rod 67 inward and
thus cause its end to engage with the end of
the pin 63 to move the latter backward far
enough to push it out of the hole in the
50 cover 51, thus freeing the printing wheel.
55 As the wheel is rotated in the printing op-
eration, the knuckle will be removed from
the head 68 so that as the wheel completes
one rotation, the detent will fall into the
hole in the cover 51, and thus prevent a
55 partial second rotation thereof or rotation
backward until the rod 67 is again operated.

backward until the rod 67 is again operated. It will be understood that in printing certain forms, particularly the amounts of checks, a series of words must be provided to enable the writing of all amounts up to any desired limit. The machine which I have illustrated is capable of writing any amount up to \$999.99. If any greater amounts are desired to be written, additional segments can be provided for that

purpose. It is necessary, however, to provide a series of numbers showing units, another showing "teens", others showing tens, hundreds, etc. By my novel device I have arranged the printing members so that a word from each of these series may be impressed on the paper with a proper space between the words regardless of whether one or more of the segments are moved so that its surfaces are out of printing relation. In Fig. 2, I have shown the machine set up to print "Two hundred twenty two dollars 22 cents". It will be noted that the "teens" segment is thrown back so that none of its printing surfaces are in printing relation. With the segments in these positions, the clamp 45 is raised or is held open by the projection 50 if the latter is provided, so that the check may be inserted between the jaws of the clamp and over the printing member 34, the guide 40 having been properly positioned to locate the edge of the check. Now the head 68 on the pin 67 is pushed inward and the wheel freed so that it may be rotated in the direction of the arrow on Fig. 1 by means of the handle 33. As soon as the printing surface "Two hundred" on the first segment contacts with the paper, the impression member 34 begins to turn with it and the paper is fed along until the end of the printing surface "Two hundred" is reached. Then further motion of the paper stops, since it is held by the clamp 45 which has been closed at the time the printing wheel began its rotation. The paper remains stationary until the next printing surface, in this instance "Twenty", contacts with the paper, when the operation is repeated, the word "Twenty" being printed and the sheet being fed through while the surface and the impression member 34 are in contact. The paper remains stationary while the "teens" segment is passing, since obviously there is nothing to contact with the impression member 34, to cause the paper to be removed. The same operation is followed with each of the printing surfaces and printing members in printing relation. It will thus be seen that the paper is moved only when a printing surface is in printing relation and is held stationary during the remainder of the time.

The spacing between the successive words carried by the different segments is obtained in the form which I have chosen for purposes of illustration by the fact that because the paper necessarily has some thickness, it will contact with the printing segment and the impression member before and after the line connecting the centers of these members is reached. This is clearly illustrated in Fig. 9 in which it is shown that if the impression member 34 were in contact with the printing surface on the segment 32 the paper would contact with each of these 120 125 130

members along the line 69, and obviously would continue to contact with them until the line 70 is reached. This space then would represent approximately the additional space which the paper would be moved between successive impressions from different segments. It will be understood, of course, that because of the yielding amount of the impression member 34, the latter will be moved downward to permit the paper to pass between the impression member and the printing segment. The stop 39 serves to limit the upward motion of the impression member 34 after one segment has passed out of contact with it and before the next one reaches it. If desired, additional motion can be given to the paper by modifying the character of the surface of the impression member 34, as, for instance, by making this surface of a yielding character. Such an arrangement is shown in Fig. 10 in which the surfaces are shown to be in contact between the lines 69' and 70'. Paper passing between such rollers would be given a motion in addition to that shown in Fig. 9, due to the yielding character of the surface.

As shown best in Fig. 9, by curving the clamping jaws 45, I secured a much more substantial hold on the sheet than I would if the surfaces were flat, and on the other hand, have a means which will permit the check to be drawn through the jaws without undue resistance. If the radius of the printing wheel on the plane 3-3 of Fig. 5 is relatively large, the printing surfaces may be curved on a radius struck from the axles 27 without unduly affecting the printing. The best results are obtained, however, if these printing surfaces are flat in the direction of the axis of the shaft 13, so that when brought into printing relation, as shown in Fig. 8, they constitute a flat printing form. It will be understood that the axles 27 may be located in any suitable place. Moreover, the segments 21-26 may be mounted on slides having a center in the axis of the shaft 13. In such case, the whole contour of the machine would be generally spherical instead of oblate spheroid, as shown in the illustrated arrangement. It will also be understood that while preferably I use the rotary impression member 34, any other suitable impression member may be substituted therefor, and that for some purposes, the surface of the support 10 alone will be sufficient.

I claim:

1. In a printing machine, an impression member, a rotatable member, a plurality of axles in said rotatable member in a plane at right angles to the axis of said rotatable member and each of said axles making an angle with the adjacent axles, a printing segment rotatably mounted on each of said

axles, each of said segments being curved longitudinally of the axis of said rotatable member and also curved in the direction of rotation of said rotatable member, each of said segments being provided with a plurality of printing forms spaced apart longitudinally of the axis of said rotatable member and curved at right angles to said axis so that when a form is brought into a plane at right angles to said axis and extending through said impression member, said form will form an arc of a circle having said axis as its center, a handle for each segment whereby it may be swung on its axle, and a detent for each segment to hold it in adjusted position.

2. In a printing machine, an impression member, a rotatable hub, a plurality of axles mounted in said hub in a plane at right angles to the axis of said hub, each of said axles making an angle with the adjacent axle, a curved printing member having a plurality of printing forms spaced apart longitudinally of the axis of said hub and curved so as to form an arc of a circle having the said axis as its center, when the form lies in a plane passing through said impression member at right angles to said axis, a curved cover connected to said hub and extending over said segments and having an opening in the plane passing through said impression member at right angles to the axis of said hub, a detent for each segment mounted on said cover and constructed and arranged to hold said segment in adjusted position, and a handle connected to each segment and extending through a slot in said cover, said cover being provided with marks adjacent each of said slots, whereby the form on each segment in printing position to coöperate with said impression member is indicated.

3. In a printing machine, an impression member, a rotatable hub, a plurality of axles in said hub adjacent the axis thereof and in a plane at right angles to the axis thereof, each of said axles making an angle with the adjacent axle, and a printing segment having a relatively long radius rotatably mounted on each of said axles, each of said axles being positioned so that the segment mounted thereon may swing in a plane radial to the axis of said hub.

4. In a printing machine, an impression member, a rotatable hub, a plurality of axles in said hub in a plane at right angles to the axis of said hub and each tangent to a circle having said axis as a center, and a printing segment rotatably mounted on each of said axles, each of said segments being curved longitudinally of said axis to form an arc of a circle with the axle of the segment as a center, the length of said radius being greater than the distance between the axis of said hub and the centers of said axles.

5. In a printing machine, an impression member, a rotatable hub, a plurality of axles in said hub in a plane at right angles to the axis thereof, a printing segment on each of said axles, the distance between the printing surface of each segment and its axle being greater than the distance between the axle and the axis of said hub, each of said segments being of approximately the same 10 length and the printing surfaces thereon being curved to form an arc of a circle passing through said impression member at right angles to said axis.
6. In a printing machine, an impression member, a rotatable hub, a plurality of axles in said hub in a plane at right angles to the axis thereof, a printing segment on each of said axles, the distance between the printing surface of each segment and its axle being greater than the distance between the axle and the axis of said hub, each of said segments being of approximately the same 15 length and the printing surfaces thereon being curved to form an arc of a circle passing through said impression member at right angles to said axis, each of said segments extending around said axis over an arc of not less than 180 degrees.
7. In a printing machine, a rotatable hub having a slot extending inwardly from its 20 surface and extending in a plane at right angles to the axis of said hub, an axle in said slot, a printing member mounted on said axle and means to hold said axle in said slot.
8. In a printing machine, a rotatable member having a hub, a plurality of axles, each 25 in a slot in said hub extending in a plane at right angles to the axis of said rotatable member, a sleeve extending over said axles for holding them in said slots, and a printing member mounted on each of said axles.
9. In a printing machine, a rotatable hub having a slot extending inwardly from its 30 surface and extending in a plane at right angles to the axis of said hub, an axle in said slot, a plurality of printing members, movable independently of each other, on said axle, and means for holding said axle in said slot.
10. In a printing machine, a rotatable hub having a slot extending inwardly from its 35 surface and extending in a plane at right angles to the axis of said hub, an axle in said slot, a printing member mounted on said axle and having a printing surface thereon, means to hold said axle in said slot, and a guide connected to said hub and contacting with said member between its printing surface and its axle, and adapted to prevent motion of said surface longitudinally of said axle.
11. In a printing machine, a rotatable printing wheel having printing surfaces extending around a portion only of the circumference of said wheel, an impression member to coöperate with said surfaces, a handle whereby said wheel may be rotated, a detent to lock said wheel in non-printing 65 position with its printing surfaces out of contact with said impression member, and means adjacent said handle to throw out said detent when it is desired to rotate said wheel.
12. In a printing machine, a fixed shaft, a support for said shaft at one end thereof, 70 a printing wheel on said shaft having printing surfaces extending around a portion only of the circumference of said wheel, a handle on said wheel on the side opposite said support, a detent constructed and arranged to engage said wheel and said support and to lock said wheel in non-printing position with its printing surfaces out of contact with said impression member and a device extending through said wheel from a point 75 adjacent said handle, constructed and arranged to throw out said detent when it is desired to rotate said wheel.
13. In a printing machine, a rotatable printing wheel having printing surfaces extending around a portion only of the circumference of said wheel, an impression member to coöperate with said surfaces, a handle whereby said wheel may be rotated and a detent to lock said wheel in non-printing 80 position with its printing surfaces out of contact with said impression member, a paper clamp to hold the sheet to be printed and means connected to said wheel to open said clamp when said wheel is locked against 85 rotation.
14. In a printing machine, a printing wheel having printing surfaces thereon, an impression member coöperating therewith and a yielding clamp for a sheet passing 90 between said wheel and said member, the jaws of said clamp being constructed and arranged to bend the paper between them in the direction of the feed of the sheet.
15. In a printing machine, a printing 95 wheel having printing surfaces thereon, an impression wheel coöperating therewith, a sheet support for a sheet passing between said printing wheel and said impression member and a sheet guard of flexible material arranged to hold the sheet down on said support, said guard having an opening 100 through which said impression wheel may extend.

BENJAMIN F. JOLINE.
